UNITED STATES PATENT OFFICE

97,308

DESIGN FOR A BOWL

Edward D. Sledge, Jr., Atlanta, Ga., assignor to Coca-Cola Company, Atlanta, Ga., a corporation of Delaware

Application July 18, 1935, Serial No. 57,709

Term of patent 14 years

To all whom it may concern:

Be it known that I, Edward D. Sledge, Jr., a citizen of the United States, residing at Atlanta, in the county of Fulton and State of Georgia, have invented a new, original, and ornamental Design for a Bowl, of which the following is a specification, reference being had to the accompanying drawing, forming part thereof.

I claim:

The ornamental design for a bowl, as shown.

EDWARD D. SLEDGE, JR.
